CALORIE INDEX OR THE LIKE

David Kirshenbaum, Cranston, and Anthony J. Iorio,
North Providence, R.I., assignors to Consumer Dynamics Inc., Providence, R.I., a corporation of Rhode Island

Filed Feb. 3, 1969, Ser. No. 15,609

Term of patent 14 years

Int. Cl. D19—02

U.S. Cl. D74—1

FIG. 1

FIG. 2

FIG. 3

FIG. 5

FIG. 6

FIG. 1 is a front elevational view of a calorie index or the like showing our new design;

FIG. 2 is a rear elevational view thereof;

FIG. 3 is a side elevational view thereof looking from the right with respect to FIG. 1;

FIG. 4 is a side elevational view looking from the left with respect to FIG. 1;

FIG. 5 is a bottom edge view thereof; and

FIG. 6 is a top edge view of the disclosure made in FIG. 2.

We claim:

The ornamental design for a calorie index or the like, substantially as shown.
